US00D931277S

(12) **United States Design Patent** (10) **Patent No.:** **US D931,277 S**
Denhez et al. (45) **Date of Patent:** **** Sep. 21, 2021**

(54) **HEADSET WITH VISOR**

(71) Applicant: **Microsoft Corporation**, Redmond, WA (US)

(72) Inventors: **Nicolas A. Denhez**, Seattle, WA (US); **Young Duk Song**, Kirkland, WA (US); **YeongKyu Yoo**, Bellevue, WA (US); **Paul A. Bosveld**, Seattle, WA (US); **Carl J. Ledbetter**, Mercer Island, WA (US); **Yuenkeen Cheong**, Sammamish, WA (US); **Michael Bohan**, Maple Valley, WA (US); **Lynda Horton-Jones**, Kirkland, WA (US); **Roy Riccomini**, Saratoga, CA (US); **Jason Paul Williams**, Santa Clara, CA (US); **Andriy Pletenetsky**, Mountain View, CA (US); **Joel B. Jacobs**, Seattle, WA (US)

(73) Assignee: **Microsoft Corporation**, Redmond, WA (US)

(**) Term: **15 Years**

(21) Appl. No.: **29/665,859**

(22) Filed: **Oct. 8, 2018**

(51) LOC (13) Cl. **14-02**

(52) U.S. Cl.

USPC **D14/372**

(74) Attorney, Agent, or Firm — Banner & Witcoff, Ltd.

(57) **CLAIM**

The ornamental design for a headset with visor, as shown and described.

DESCRIPTION

FIG. 1 is a top front perspective view of a headset with visor showing our new design;

FIG. 2 is a top rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The even-length broken lines depicting the remainder of the headset with visor show features that form no part of the claimed design. The uneven-length broken lines adjacent to the shaded region depict the boundary of the claimed design and forms no part thereof.

1 Claim, 8 Drawing Sheets
